UNITED STATES PATENT OFFICE.

JOSEPH A. BRADBURN, OF SYRACUSE, NEW YORK.

FURNACE.

No. 911,550.

Specification of Letters Patent.

Patented Feb. 2, 1909.

Application filed June 27, 1908. Serial No. 440,645.

To all whom it may concern:

Be it known that I, JOSEPH A. BRADBURN, a citizen of the United States of America, and residing at Syracuse, in the county of 5 Onondaga and State of New York, have invented a certain new and useful Improvement in Furnaces, of which the following is a specification.

My invention relates to furnaces and particularly to down draft furnaces, the object of my invention being to produce a simply constructed furnace of the down draft type which will effectually consume the coal gases and smoke, and may be either fitted to a 10 stove, range, or other heating appliance of the ordinary type or form an integral portion of an independent structure.

In the accompanying drawings, Figure 1 is a vertical section of a furnace illustrating my 20 invention in one form; Fig. 2 is a section of the same at right angles thereto; Fig. 3 is a front elevation of the same; Fig. 4 is a vertical elevation partly in section showing my device applied to a hot air furnace; Fig. 5 is a 25 similar view showing my device applied to a plurality of air heaters; Fig. 6 is a similar view showing a range supplied with my device; and Fig. 7 is a similar view of a furnace in which my device is incorporated as an integral part.

Referring to the drawings my device in the form shown, comprises a fire box 10, suitably lined with fire brick 11, carried by a casing 12, of any suitable material, for example cast 35 or sheet iron. A grate 14 separates the fire box from the ash pit 15 into which the ash pit door 16 and the bottom draft regulator 17 open as is customary. The port 13 permits the feed of fuel to the fire box and also acts 40 as an air inlet as hereinafter described. Surrounding the casing 12 and separated therefrom by an air space, I mount on brackets 19 a hood 18 which extends down to the ash pit. This hood may be constructed in any suit- 45 able manner, but preferably comprises an outer shell 20 of sheet or cast iron and an inner lining 21 of sheet iron with a heat insulator 22 (asbestos, fire brick, air or other suitable substance) separating the same. A 50 hinged feed door 23 opens opposite the port 13 and carries a plate 24 mounted on the screw 25 by which the admission of air through the port 13 may be suitably regulated by means of the handle 26. Poker 55 holes 27 are opened as desired through the face and sides of the fire box and hood, the

space between the hood and casing 12 being occupied at these points by hollow cones 28. Swinging covers 29 are fitted over the holes to prevent the escape of dust or gases from 60 the fire box. By using the poker through the various poker holes, the fire may be well stirred and passages for air made in any direction through the body of the fuel. One or more outlet flues 30 placed low in the fire 65 box and below the normal level of the fuel open from the back (Fig. 1) or side (Fig. 5) of the fire box. This outlet flue may extend across the entire back of the fire box, as shown in Fig. 2, in order to give an ample draft. 70

To prevent the escape of ash which may be carried to the flue and dropped down in the air space between the casing 12 and the hood 18, I arrange an apron 31 beneath the flue and open a passage into the ash pit at 75 this point so that the ashes falling from the flue 30 will be carried down into the ash pit. A slide 32 may be arranged in this passage in order to regulate the size of the opening for the purposes hereinafter referred to. A 80 small flue 33 in the top of the fire box, closed by a damper 34, is arranged to permit the escape of gases from the fire box to the air space between the hood and the casing 12. A second damper 35 may be arranged at 85 another point in this air passage to permit the regulation of the flow of air or gas there-through.

The operation of this furnace is as follows. With the damper 17 open to full capacity 90 and the damper 35 closing the air passage between the hood in the casing and the plate 24 screwed down tight and the slide 32 closed; a fire is built in the fire box, all the draft coming from below. After the fire is 95 well started the damper 17 may be closed and then the plate 24 screwed out so as to permit the air which is drawn up underneath the hood to enter the fire box through the port 13 thus opening a down draft to the 100 fire. It will be noted that inasmuch as the lower edge of the hood is below the outlet flue 30, the arrangement produces a siphon-like action. If from any reason the chimney draft is disturbed or weak, the gases in 105 the furnace rise to the top of the fire box and may enter the air space between the hood and the casing, but they will not descend to the opening at the bottom of the hood because they are opposed by the incoming 110 draft of air which tends to carry them up and out through the flue 30 which is above the

bottom of the hood. Should the gases and smoke be incompletely consumed, the damper 35 is swung down so as to permit the air to flow through the passage between the hood and the casing into outlet flue 30 where the hot gases and smoke will be consumed.

It will be noted that the air before it reaches the flue 30 has traversed the passage over the fire box and has therefore, been considerably heated which adds to its efficiency in securing the combustion of the gases. Should the combustion of the gases be still incomplete, damper 17 and the slide 32 may be slightly opened, so that the air entering the ash pit through the damper 17 will not only feed the fire from below, but will be drawn through the slide 32 to the gases in the flue 30 and there aid in the combustion thereof. It will be understood that the fire brick lining of the fire box which confines the heat from the combustion of the coal so heats the gases that they are of sufficiently high temperature to undergo complete combustion by the supply of air coming from above or below to the flue 30 when said gases have not been consumed in the fire box itself. Such gases as may rise into the space above the fuel in the fire box escape therefrom either through the port 33, when the damper 34 is raised, or through the port 13 when the plate 24 is screwed out and flow with the air beneath the hood to the flue 30.

35 This furnace while capable of burning hard coal, is particularly adapted to burn soft coal and may be attached to any of the ordinary stoves, ranges and furnaces in use for domestic purposes, although a special opening for a pipe from the flue 30 may be necessary in some cases to prevent functional derangement.

In Fig. 4 I have shown my furnace attached to an ordinary hot air furnace. The flue 30 is conducted by a special opening to the fire box of the latter and heats the furnace in precisely the same manner as it would be heated were a fire to be built therein.

59 In Fig. 5 the flues 30 open into heating drums 35 which are located within hot air chambers 36.

In Fig. 6 my furnace is attached to an ordinary cooking range and furnishes the heat otherwise supplied by the combustion of fuel therein.

In Fig. 7 I have shown my furnace forming an integral part of a hot air generator which has the advantage that the heating chamber for the air is low and thus permits the hot air pipes leading to the registers to rise therefrom at a sharper angle than is now generally possible with the hot air furnaces in general use.

65 In cases in which my furnace is applied to

ranges, stoves or furnaces already provided with fire boxes, it is to be understood that the flue from my furnace may be connected therewith at any desired point such that the draft or heating system is not deranged. 70

Many modifications of my device will readily suggest themselves to those skilled in the art and I do not limit myself to the construction shown.

I claim as my invention:

1. A furnace of the down draft type, having a grate and ash-pit an inclosed fire box and an outlet flue opening therefrom above the grate but below the upper surface of the fuel, in combination with a down draft conduit opening into the fire box above the surface of the fuel and having a suction intake opening to the atmosphere at a point below the outlet flue. 75

2. A furnace of the down draft type, having a grate and ash-pit an inclosed fire box and an outlet flue opening therefrom above the grate but below the upper surface of the fuel, in combination with a hood over said fire box spaced therefrom to form an air passage extending below the outlet flue and opening to the atmosphere at its lower edge and an inlet from said air passage above the upper surface of the fuel to permit down draft to the fire, substantially as described. 80

3. A furnace of the down draft type, having a grate and ash-pit an inclosed fire box and an outlet flue opening therefrom above the grate but below the upper surface of the fuel, in combination with an air supply conduit having a suction intake below the level of said flue and passing over said fire box to the latter, together with means for supplying the fire with a down draft therefrom from a point above the surface of the fuel. 85

4. A furnace of the down draft type, having a grate and ash-pit an inclosed fire box and an outlet flue opening therefrom above the grate but below the upper surface of the fuel, in combination with an air supply conduit having a suction intake below the level of said flue and passing over said fire box to the latter; said fire box having a controlled port opening through its top into said conduit as and for the purposes described. 90

5. A furnace of the down draft type, having a grate and ash-pit an inclosed fire box and an outlet flue opening therefrom above the grate but below the upper surface of the fuel, in combination with an air supply conduit having a suction intake below the level of said flue and passing over said fire box to the latter, said fire box having a controlled port opening through its top into said conduit and means for admitting a supplemental air supply to the flue from the ash pit, substantially as described. 95

6. A furnace of the down draft type, having a grate and ash-pit an inclosed fire box and an outlet flue opening therefrom above

the grate but below the upper surface of the fuel, in combination with a hood over said fire box spaced therefrom to form an air passage extending below the outlet flue and opening to the atmosphere at its lower edge and an inlet from said air passage above the upper surface of the fuel to permit down draft to the fire, said fire box having a plurality of poker holes opening through said hood and fire box walls at different levels above the grate, substantially as described.

7. A furnace of the down draft type, having a grate and ash-pit an inclosed fire box with outlet therefrom above the grate but below the surface of the fuel, a hood extending over and around the same and spaced therefrom to afford an air passage, said hood extending below the outlet flue and there opening to the atmosphere, a fuel feed port opening through said hood and fire box wall and means for admitting a down draft therethrough to the upper surface of the fuel from the space between the hood and the fire box, substantially as described.

8. A furnace of the down draft type, having a grate and ash-pit an inclosed fire box with outlet therefrom above the grate but below the surface of the fuel, a hood extending over and around the same and spaced therefrom to afford an air passage, said hood extending below the outlet flue and there opening to the atmosphere, a fuel feed port opening through said hood and fire box wall, a door closing the port in the hood, a plate carried thereby for closing the port in the fire box wall and means to control the position of said plate whereby a down draft may be admitted through the port in the fire box wall to the upper surface of the fuel from the space between the hood and the fire box, substantially as described.

In testimony whereof I have signed my name to this specification, in the presence of two subscribing witnesses.

JOSEPH A. BRADBURN.
